UNITED STATES PATENT OFFICE.

EDOUARD FREDERIC DELAPERRIERE AND LOUIS CHAMBON, OF PARIS,
FRANCE, ASSIGNORS TO SAID CHAMBON AND THE SOCIÉTÉ DELA-
PERRIÈRE DIDA ET AUBIN, OF SAME PLACE.

MACHINE FOR AUTOMATICALLY ROLLING PAPER TUBES.

SPECIFICATION forming part of Letters Patent No. 596,262, dated December 28, 1897.

Application filed April 17, 1896. Serial No. 588,003. (No model.)

To all whom it may concern:

Be it known that we, EDOUARD FREDERIC DELAPERRIERE, manufacturer, and LOUIS CHAMBON, engineer, citizens of the French Republic, residing at Paris, in the Department of the Seine, France, have invented certain new and useful Improvements in Machines for Rolling Automatically Paper Tubes, of which the following is a specification.

Our invention relates to a machine for making complete paper and pasteboard tubes of different diameters and sections.

This machine is characterized by the combination of the following constituent parts: a spool upon which the paper is rolled, which unwinds under a slight tension by the working of the machine and passes then under a pan with glue, where it is sufficiently impregnated with adhesive matter; a series of mandrels upon which the paper coming from the spool after having previously been impregnated with adhesive matter is wound; two cylinders applying the paper successively upon each of the mandrels while it revolves, a cutter, dropping by the action of a disengaging device, serving to cut the paper when the roll is of the required thickness; rubber pincers which after the paper has been cut paste its free end upon a new mandrel, and, finally, a series of mechanical devices bringing, successively, each of the mandrels in position and ejecting the formed tubes.

The invention is illustrated in the accompanying drawings, in which—

Figure 1 shows a sectional view in elevation of the whole of the machine on the line Y' Z' of Fig. 2. Fig. 1^a is a view of the right-hand part of the machine, this figure being an extension of Fig. 1; Fig. 2, a sectional plan of the same on the line V X of Fig. 1. Fig. 2^a is a plan view of the right-hand part of the machine, showing an extension of Fig. 2; Fig. 3, a longitudinal section along the axle of the mandrel and of the wheel, Fig. 1; Fig. 4, a sectional view in elevation of said machine on the line V' X' of Fig. 3; and Fig. 5, another sectional view in elevation on line Y Z of figure with parts broken away. Fig. 6 represents, on a larger scale, a plan view through the shaft of the cams K'. (See Fig. 1.) Fig. 7 is a hori-

zontal cross-section taken through the lines 1 2 of Fig. 6. Fig. 8 is a side elevation of the upper parts of Figs. 6 and 7. Figs. 9, 10, 11, 12, 13, and 14 are details of the lower parts of Fig. 1. Fig. 15 represents the detail drawing of the glue-reservoir in a position to apply the glue. Figs. 16 and 17 are, the first one, a front view, and the second a cross-section, of one of the wheels of the drum. Figs. 18 and 19 show as elevation and as plan the details of the means serving to withdraw the mandrels and to put them in place again.

The tubes are formed upon mandrels B B⁷, carried by a rotary support or carrier comprising the two side plates D D', between which the mandrel extends parallel with the axes of the plates. The plates are connected with each other also by eight cross-pieces E E⁷, each carrying a counter-cutter N N⁷, hereinafter referred to.

The mandrels are adapted to slide through sockets O, fixed upon the plate D, Fig. 3. Eight arms D² are arranged upon the outer surface of the plate D, by which, as herein-after described, the mandrel-carrier is moved step by step about its axis. The paper, in web form, from which the tube is to be made passes from any suitable source of supply over the roller A', which is driven by the gearing H H'. (Indicated in Fig. 1.) From this roller the paper web passes to the glue-pan G and around the cylinder A² therein and between said cylinder and the cylinder A⁴ to the winding mechanism. These cylinders are shown at the right of Fig. 1.

The distribution of the glue is regulated by screws g, passing through brackets in the glue-pan and bearing at their lower ends upon the rearwardly-extending part X of the pan-supporting frame. By these screws the pan can be raised or lowered to alter the position of the scraper g', carried by the pan, relative to the glue-roller A², which, as shown in Figs. 1 and 15, closes the lower open end of the pan. Two plates g² g³ are arranged within the pan to be adjusted laterally thereof by means of the screws g^X, Figs. 1 and 2, to suit different widths of paper. After receiving the paste the web passes between the rollers A² A⁴ over a guide A³, arranged adjacent to

the rotary carrier-plates D D', and thence to one of the mandrels, Fig. 1 showing the paper being wound on the mandrel B. These mandrels are brought in succession between the 5 paper-rolling cylinders C C', Figs. 1 and 13, the cylinder C being carried by an oscillating lever C^x, pivoted on an axis 10, supported in a bracket 11, Figs. 1 and 3, which is in turn supported on the main shaft. This roller is turned by the gear 1 on the main driving-shaft, Figs. 1 and 3, the intermediate gear 2, the gear 3 on the axis 12 of the carriers D D', the gear 4, and the gears 5 and 6, (see the dotted lines, Fig. 1,) the former, 5, being on the axis 10 of the arm C^x, while the latter gear is connected with the rolling-cylinder C. The lower rolling-cylinder is carried by a lever T, pivoted on the axis T^x, Figs. 1 and 13, in a standard, and this rolling-cylinder is positively 20 driven through the gearing 7, 8, and 9, Figs. 1 and 3, the gear 7 being on the main driving-shaft, the gear 8 being on the axis T^x of the lever T, and the gear 9 being on the axis of the rolling-cylinder.

25 The carrier, comprising the plates D D' and the cross-bars Q, is designated as D^x, and while this carrier is making its step-by-step movement the upper rolling-cylinder is raised by the roller 14 on the lever C^x, Figs. 1 and 13, riding on one of the high parts U^x of the cam U, which rotates with the carrier. The movement of the carrier thus separates the rolling-cylinders and at the same time it enters the mandrel between the cylinders and 30 thereupon the roller 14, falling into one of the low parts or depressions of the cam V, allows the cylinder C, under the action of the spring 15, to fall upon the mandrel and roll the paper about the same in conjunction with 35 the lower rolling-cylinder. When the required amount of the web has been rolled about the mandrel by the positive action of the rolling-cylinders, the lower rolling-cylinder having partaken of the separating movement 40 of the cylinders will have moved the lever T down far enough to make the screw I, carried thereby, bear upon a pin I^x in a lever I², Figs. 6, 9, 10, 13, and 14. This lever is also carried down and thus it releases its hooked end 45 16, Fig. 9, from an arm I³, fixed on a shaft I⁴. This shaft also carries the arm C⁴, Figs. 1 and 11, which up to this time has been holding down the plunger-rod 17, Fig. 11, as indicated in dotted lines, against the pressure of the 50 spring C⁶. As soon as the catch-arm I³ is released this spring C⁶ becomes effective and forces the plunger upward. At its upper end this plunger carries the pincers C³ and the cutter C², and when the plunger moves upward 55 the cutter C², acting in conjunction with the counter-cutter N, Fig. 11, severs the web and forces the free end thereof upon the mandrel, which at this time is directly in the path of the pincers, which have a concave face 60 adapted to fit the cylindrical form of the mandrel. The parts of Fig. 11 are shown as operating in connection with the mandrel B⁷.

The portion of the paper cut off continues to be wound upon the mandrel B until the tube being formed thereupon is completed. The lever T is carried by the frame I', which is under tension of the spring 18. During all this winding action the carrier D^x has remained at rest.

When the shaft I⁴ is rocked to release the cutter and pincers mechanism, it also releases a pivoted lever I⁵, Figs. 2, 4, 6, 7, and 8, by withdrawing the catch or lug I⁶ from engagement with the catch-lug 19 on the said lever. This lever then, under the action of the spring 20 i, Fig. 2, is drawn from the position shown in dotted lines, Figs. 2 and 6, to that shown in full lines, and this catch throws the friction-gear J into work. The outside shell portion J^x of this clutch rotates loosely on a shaft 25 K', being driven constantly through the gears R and R', Figs. 2, 3, 6, 7, and 8, while the inner part J is splined to the shaft K', so that when J is thrown into action the shaft K' will be turned, and through a pinion K² thereon and a gear K² on the cam-shaft K the latter shaft will be rotated. This shaft carries the lever K⁴, Figs. 1 and 16, which, operating upon the arms D² of the carrier D^x, moves the same one step to remove the mandrel B, with its 30 completed tube, from between the rolling-cylinders and to bring a fresh mandrel between said cylinders. A cam C³, Fig. 9, on this shaft K, acting through a roller-arm C⁷, Figs. 1 and 9, returns the detent-shaft I⁴ to its normal position, so that in this action the pincers and cutter are withdrawn from the mandrel B⁷ to allow the same to move to the rolling-cylinders, this retracting movement being effected through the lever C⁴. The cam-shaft also 35 carries a cam K⁵, having a peripheral groove receiving a roller on a rocking lever F⁷, Fig. 3, the slotted end of which engages a pin 20, Figs. 18 and 19, on a block 21, sliding in guideways 22 and having a forked end 23 to receive the heads b of the mandrels as they come around to the point at which the retracting-block is located, when the heads engage with the forked end of the block. The lever F⁷ is operated by the cam K⁵, and the 40 block is retracted from the carrier D^x, thus drawing the mandrel out through the sleeve O and stripping the completed tube therefrom, which falls into any suitable receptacle. This discharging action takes place, 45 of course, while the carrier D^x is at rest. The mandrel is returned to normal position again by the lever K⁴ before the carrier makes another step.

A cam-rib K⁶ on the gear K² of the shaft 50 K engages a roller K⁷ on the clutch-gear-controlling lever I⁵ and moves this back so as to be in position to be engaged and held by the detent-catch I⁷ when the latter is moved by the return of the detent-shaft I⁴ to normal 55 position.

A cam-surface K⁸ on the cam-rib K⁶ moves the lever L, Fig. 7, laterally, and thus withdraws the detent l from engagement with

the lever I^6 . This lever then, under the action of its spring i' , is moved so that the friction-gear J is thrown out and all the parts—viz., the carrier-moving devices, the pincers and cutter resetting mechanism, and the discharge mechanism—are stopped and only the rolling or winding mechanism is in operation.

The levers I^5 I^6 are jointed to each other at M , or, rather, they pivot about the same axis. The spring i of lever I^5 is stronger than the one of the lever I^6 , and when the lever I^5 is released from the detent I^7 both levers I^5 and I^6 are moved, so that the clutch J may be thrown in, the latter lever, I^6 , moving with the lever I^5 by a pin I^8 on the lever I^6 , projecting down into the path of the edge of the lever I^5 . This throwing in of the clutch sets the lever I^6 in engagement with the detent l of the releasing-lever L , so that at the proper time the lever I^6 will be released to set the clutch free, the throwing-in lever I^5 having been set at this time into engagement with the detent I^7 , which of course will leave the throw-out lever free to act when released by the lever L . The parts of the clutch are pressed together by a spring l^2 .

The action of the pincers C^8 , which are rubber-faced, is to paste the end of the web upon the mandrel, and in order to effect a slight preliminary winding of the web about the mandrel as it is leaving the pincers and before it arrives at the rolling-cylinders we mill the heads b of the mandrel and cause them to engage with a fixed section S , Fig. 1, outside the carrier.

We claim—

1. A machine for making tubes, consisting of a rotary step-by-step carrier with means for operating the same, the series of mandrels carried by the carrier for winding the strip of material, means for applying glue to the material, rolling-cylinders for rolling the material upon the mandrels, a cutter, a counter-cutter acting in conjunction with the main cutter for severing the material when the tube has been wound to the proper thickness, pincers for pressing the free end of the material upon a new mandrel and means for operating the mandrels to and from position to eject the tubes, substantially as described.

2. In a tube-making machine, the mandrels, the carrier therefor comprising the side plates between which the mandrels extend and through one of which the mandrels slide, means for operating the mandrels longitudinally and paper rolling and cutting devices, comprising the upper and lower rollers and main and counter cutter and the reciprocating pincers for pressing the end of the web upon the next succeeding mandrel said pincers carrying the cutter and said parts being arranged intermediate of the side plates, substantially as described.

3. In a tube-making machine, the mandrels, the cutters, the carrier therefor comprising the two side plates, winding mechanism for

the material, one of said cutters being arranged adjacent to each one of the mandrels, and a main cutter and pincers operating to sever the paper and to apply the free end of the web upon the next mandrel, substantially as described, the cross-pieces extending between the side plates and carrying cutters for the material, substantially as described.

4. In combination a series of mandrels, a step-by-step rotary carrier for the same, a pair of rolling-cylinders adapted to open and close, and arranged to receive the mandrels between them in succession, cutting mechanism for the web, and means for applying the free end of the web to a fresh mandrel, substantially as described.

5. In combination, the mandrels, the carrier therefor, the rolling-cylinder, means for supporting the same yieldingly, the cutter and pincers device with means for operating the same controlled by the yielding cylinder when the tube is of the proper size, the counter-cutter, said main cutter and pincers device acting to sever the material and to hold the free end of the web against the next mandrel, and a carrier for the mandrels to bring them in succession to the rolling-cylinders and to the cutter, and pincers, substantially as described.

6. In combination, the step-by-step carrier, a pair of yielding rolling-cylinders adapted to open and close, the mandrels carried by the carrier to be brought between the rolling-cylinders, a cam moving with the carrier for opening and closing the rolling-cylinders, and a cutting device controlled by the separating movement of the cylinders in forming the tube, substantially as described.

7. In combination, the step-by-step carrier, driving mechanism therefor, a clutch controlling the same, a series of mandrels, a pair of rolling-cylinders adapted to receive the mandrels between them, a cutter mechanism and operating connections from one of the rolling-cylinders to said cutting mechanism and to the clutch to control the same when the tube reaches a certain size, substantially as described.

8. In combination, the step-by-step carrier, the rolling-cylinders driving mechanism, a cutter and pincers mechanism, a discharge mechanism, a cam-shaft, a cam thereon for operating the discharge mechanism, means for resetting the cutter and pincers mechanism including a detent-shaft with means to operate the same from one of the rolling-cylinders, and a clutch controlled by the detent-shaft for controlling the cam-shaft, substantially as described.

In witness whereof we have hereunto set our hands in presence of two witnesses.

EDOUARD FREDERIC DELAPERRIERE.
LOUIS CHAMBON.
